R. L. BLACK

LUBRICATOR

Filed May 24, 1926

UNITED STATES PATENT OFFICE.

ROBERT L. BLACK, OF ROANOKE, VIRGINIA.

LUBRICATOR.

Application filed May 24, 1926. Serial No. 111,321.

The invention relates to lubricating apparatus and has particular reference to means for applying lubricant to the flanges of locomotive and car wheels.

- 5 The principal object of the invention, generally stated, is to provide a novel device adapted to be mounted upon a wheel to be lubricated, the device including a reservoir member which is floatingly mounted so as 10 to be supported by the flange of the wheel to be lubricated, the reservoir member consequently accommodating itself to variations in the distance between the wheel and the rigid frame, it being well known that owing 15 to the action of the springs in the trucks this distance necessarily varies during car travel.

An important object of the invention is to provide a lubricating device embodying a supporting structure and a reservoir member 20 mounted therein in such a manner that not only will vertical movement of the reservoir member be permitted, but also limited rocking movement in a vertical plane and free lateral movement, the latter being of 25 particular advantage in making the device able to accommodate itself in case of any lateral movement of the car wheels with respect to the rigid frame.

A still further object of the invention is 30 to provide a lubricating device of this character in which is embodied a reservoir member so constructed and arranged that lubricant will be fed from an oil chamber through the capillary action of a wick-like packing 35 of absorbent material which bears upon the flange to be lubricated so that only sufficient oil will be fed thereto to lubricate the outer face of the flange without danger of the oil running down upon the wheel tread and 40 causing slipping of the wheel with respect to the tracks.

A further object of the invention is to provide a lubricating device of this character embodying an extremely simple supporting bracket for mounting the reservoir member, the bracket permitting the necessary vertical and lateral play of the reservoir member while preventing it from turning over at any time.

50 An additional object of the invention is to provide an apparatus or device of this character which will be simple and inexpensive in manufacture, easy to install, automatic in operation, efficient in action, durable in service, and a general improvement in the art.

With the above and other objects and advantages in view, the invention consists in the details of construction and arrangement of parts to be hereinafter more fully described and claimed, and illustrated in the accompanying drawings in which:

Figure 1 is a perspective view of the device showing it mounted upon a rigid support and engaging a wheel flange to be lubricated.

Figure 2 is a vertical longitudinal section through the reservoir member and the bracket.

Figure 3 is a vertical cross section taken 70 on the line 3—3 of Figure 2,

Figure 4 is a fragmentary end elevation of the reservoir member, and

Figure 5 is a cross sectional view therethrough taken on the line 5—5 of Figure 1. 75

Referring more particularly to the drawings I have shown the device as comprising a reservoir member indicated generally by the numeral 1, which reservoir member preferably includes a body 2 of substantially rectangular shape with a depending extending portion 3 thereon. The reservoir member may conveniently be formed as a casting though there is no particular limitation desired in this respect. The body portion 2 is 80 of hollow formation and is provided with a transverse partition 4 which defines a lubricant chamber 5 and a passage 6 which leads to a discharge opening 7 in the extension 3. This extension is represented as curved in 85 cross section to define a wall 8 which corresponds substantially to the curvature of the flange A of a wheel B to be lubricated. One side wall of the reservoir member is preferably formed with an enlargement, thickened 90 portion or projection 9 which extends partly across the passage 6 so as to constrict the discharge opening 7. It is intended that the reservoir member be filled with absorbent material 10, such as cotton waste, this material dipping into the lubricant chamber or well 5 and filling the passage 6, the end of the mass of packing or wicking extending to the discharge opening 7 so as to bear against the wheel flange A. The projection 9, by 95 constricting the discharge opening, causes the absorbent material to engage only against that portion of the flange which contacts with the rail during car travel.

When the device is mounted by means to 110 be described, it is intended to float and be supported only by the flange of the wheel

and it will be observed that at one side of the discharge opening 7 the end of the extension 3 is inclined, as shown at 11, so as to be close to the tread C of the wheel without actually engaging against it. The opposite side wall of the extension 3 may be inclined in the opposite direction as shown at 12 so as to define a triangular extension 13 located inwardly of the wheel and acting as a guide for the reservoir member. The projection 9 is represented as inclined to correspond to the inclination of the edge 12 and the top surface 14 of this projection is preferably inclined downwardly toward the opposite side wall of the reservoir member so as to facilitate placing the absorbent material in position and forcing it into the passage 6 and to the discharge opening 7, when the reservoir member is packed. It is preferable that the lower edge portion 11 of the extension 3 have an inwardly extending rib 15 which is intended to bear against the outside of the wheel flange to prevent lubricant from running down onto the wheel tread C. To facilitate replenishing the oil supply and repacking of the reservoir member with absorbent material whenever such is necessary, I preferably provide the reservoir member with a cover 16 which extends over the entire open top, this cover being hinged as at 17 and being provided with an extension 18 constituting a finger piece, and equipped with a spring catch 19 for holding it normally closed.

In order that the reservoir member 1 may be mounted upon a supporting structure to be described, I have shown it as provided at one side edge with upper and lower pairs of spaced ears 20 apertured for the passage of bolts 21. While it is conceivable that different detailed mounting means might be provided, I have shown an arm 22 suitably secured to and projecting from the front portion of the car or locomotive frame, this arm carrying a depending inverted U-shaped bracket 23 having its opposite sides formed with elongated slots 24 through which the bolts 21 extend, the pairs of ears 20 being located within the bracket. It will be observed that the space between the arms of the bracket is greater than the width of the reservoir member so that the reservoir member will be free to move laterally within the bracket and to slide upon the bolts 21 in accordance with any lateral movement of the car wheels with respect to the lubricating device.

In the operation, it is of course apparent that the reservoir member rests upon the flange of the wheel to be lubricated, the inclined edge 11 of the extension 3 permitting the reservoir member to fit down close to the wheel tread. Of course, the packing or absorbent material 11 bears against that portion of the flange which engages the rail but is prevented from touching the flange at the area immediately adjacent the tread. The absorbent material acts as a wick and, by capillary action, conducts oil from the well 5 to the wheel flange. The rib 15 on the side wall of the reservoir member acts to prevent the oil from running down onto the wheel tread and there is consequently no danger of oil coming upon the tread and therefore on top of the rail, a condition which would naturally result in slipping of the wheels. As mentioned above, the reservoir member is capable of lateral movement with respect to the bracket 23 and also vertical movement, the latter being permitted by the slots 24 when there is relative vertical movement of the wheel and car or locomotive frame as is bound to occur during travel. The extension 13 at the inside of the wheel acts as a guide and it might be mentioned that the major portion of the surface of this extension is preferably depressed as at 25 to minimize the area bearing against the wheel, friction being consequently reduced. It is intended that the space between the rib 15 and the edge of the extension 13 be substantially the same as the thickness of the wheel flange to prevent leakage of oil onto the wheel tread. Regardless of whether the locomotive or car equipped with the device be moved forwardly or rearwardly it is obvious that the reservoir member cannot turn over as there are two bolts 21 passing through the slots in the bracket. These bolts are preferably of appreciably less diameter than the width of the slots so that a limited rocking movement of the reservoir member in a vertical plane will be possible, the reservoir member being consequently capable of accommodating itself to all positions which may be assumed by the wheel with respect to the car or locomotive frame.

In actual practice I have discovered that a device constructed, assembled and mounted as shown and described acts most efficiently to lubricate wheel flanges so that rolling stock may travel more freely upon the rails inasmuch as friction will be reduced to the minimum. Naturally, this results in longer life of the rails and the wheels as the wear is reduced. Less power will be required in starting and in running and it is clear that all the advantageous results have been attained.

While I have shown and described the preferred embodiment of the invention, it should be understood that the disclosure is merely an exemplification of the principles involved inasmuch as I reserve the right to make all such changes and modifications as will widen the field of utility and increase the adaptability of the invention, provided such variations constitute no departure from the spirit of the invention or the scope of the claims hereunto appended.

Having thus described the invention, I claim:

1. In a wheel flange lubricator, a rigid supporting arm, a depending inverted U-shaped bracket carried by said arm and having its opposite sides formed with elongated slots, a reservoir member containing lubricant and absorbent material and resting upon the flange to be lubricated, and transverse elements carried by the reservoir member and extending through said slots to permit vertical movement of the reservoir member with respect to the flange, the reservoir member having a width less than the space within the bracket to permit lateral movement of the reservoir member.
2. In a wheel flange lubricator, a reservoir member resting upon and supported by the flange to be lubricated, upper and lower pairs of spaced ears on the reservoir member, a rigidly mounted depending inverted U-shaped bracket, said ears being located within the confines of said bracket, and means carried by the ears and slidably connected with the bracket to permit vertical movement of the reservoir member, the width of the pairs of ears being less than the space within the bracket to permit lateral movement of the reservoir member with respect to the bracket.
3. In a wheel flange lubricator, a support, and a reservoir member movably mounted within the support and formed as a hollow body provided with a depending extension bifurcated and shaped for straddling engagement upon a wheel flange, the bottom of the extension being inclined and formed with a constricted opening, the edge of one wall of the extension below the opening being formed with an inwardly extending rib engaging against the outer face of the wheel flange.
4. In a wheel flange lubricator, a support, and a reservoir member movably mounted within the support and formed as a hollow body provided with a depending extension bifurcated and shaped for straddling engagement upon a wheel flange, the bottom of the extension being inclined and formed with a constricted opening, the edge of one wall of the extension below the opening being formed with an inwardly extending rib engaging against the outer face of the wheel flange, the opposite wall of the extension being oppositely inclined to the first named wall and having its major portion depressed to define ribs bearing against the inner face of the wheel flange.
5. In a wheel flange lubricator, a support having sides formed with elongated slots, a lubricant reservoir member resting upon the flange to be lubricated, and means carried by the reservoir member and extending through said slots to permit vertical movement of the reservoir member with respect to the flange, the reservoir member having a width less than the space within the support to permit lateral sliding movement of the reservoir member with respect thereto.
6. In a wheel flange lubricator, a support including depending side portions, a lubricant reservoir resting upon the flange to be lubricated and supported thereby, and means carried by the reservoir member and slidably engaging the sides of the support to permit vertical sliding movement of the reservoir member with respect thereto, the reservoir member being of less width than the space within the support to permit lateral sliding movement of the reservoir member with respect thereto.

In testimony whereof I affix my signature.

ROBERT L. BLACK.
